Victor J. Evans
ATTORNEY.

UNITED STATES PATENT OFFICE.

ESTHER B. FINK, OF CHARLESTON, WEST VIRGINIA.

SHOE-LACE TIP.

1,364,044.

Specification of Letters Patent. Patented Dec. 28, 1920.

Application filed November 25, 1919. Serial No. 340,478.

To all whom it may concern:

Be it known that I, ESTHER B. FINK, a citizen of the United States, residing at Charleston, in the county of Kanawha and 5 State of West Virginia, have invented new and useful Improvements in Shoe-Lace Tips, of which the following is a specification.

This invention relates to laces generally, 10 and has for its primary object the provision of a tip for each end of the lace, which can be cheaply manufactured and applied and when associated with the ends of the lace, it is held in a manner to prevent it from being 15 casually pulled off under any and all conditions.

To this end, the tip comprises a length of bendable metal having a pair of bendable tongues stamped therefrom, the tongues being 20 arranged to be bent toward each other and longitudinally of the metal so that when the tongues are passed through the lace and bent to active position, the tongues will lie partly overlapped, to effectively confine the 25 lace between the body of the tip and said tongue.

The nature and advantages of the invention will be better understood when the following detail description is taken in connection 30 with the accompanying drawings, the invention residing in the combination and arrangement of parts as claimed.

In the drawings forming part of this specification like numerals of reference indicate 35 similar parts in the several views and wherein:

Figure 1 is a plan view of the tip forming the subject matter of my invention.

Fig. 2 is a view of one end of the lace 40 showing the strip applied thereto.

Fig. 3 is a longitudinal sectional view taken therethrough.

Fig. 4 is a transverse sectional view taken on the line 2—2 of Fig. 2.

The tip forming the subject matter of my 45 invention comprises an elongated strip of metal 10 and having stamped therefrom a pair of bendable tongues 11. The tongues as shown in Fig. 2 are arranged to be bent 50 toward each other and longitudinally of the strip 10, so that when the tongues are in active position the coöperation will effectively maintain the tip associated with the lace in a manner so that it cannot be 55 casually pulled therefrom in the usual well known manner. In practice, the tongues 11 are passed through the fabric or lace 12 in

addition to bending the tongues toward each other to partly overlap the tongues, the tongues are bent at an angle as shown to 60 cover the maximum width of the fabric and thus effectively confine the fabric between the tongues and the strip 10.

In this manner, the strip is positively secured to the end of the lace. Subsequent to 65 the arrangement of the tongues in the manner described, the strip 10 is rolled so that the opposite longitudinal edges will be arranged in overlapping relation. The construction and arrangement of parts is such 70 that the strip can be cheaply manufactured and also applied to the lace in a quick and easy manner. It is to be understood that a general application of the invention is contemplated, or in other words that the tip can 75 be used in conjunction with any type of lace.

While I have shown and described what I consider the preferred embodiment of the invention, I desire to have it understood that I do not limit myself in this connection and 80 that such changes may be resorted to when desired as fall within the scope of what is claimed.

Having thus described my invention what I claim as new is:

1. In combination with a lace, a tip therefor comprising a strip of metal and a plurality of tongues projecting therefrom and arranged in the same longitudinal plane and adapted to be passed through the lace and 90 bent longitudinally of the strip toward each other, said strip being rolled in tubular form.

2. In combination with a lace, a tip therefor comprising a strip of metal, a plurality 95 of tongues cut therefrom and arranged in the same longitudinal plane, and adapted to be passed through the strip and toward each other in overlapping relation, and said strip being rolled in tubular form.

3. In combination with a lace, of a tip therefor, comprising a strip of metal, a plurality of tapered tongues projecting from the strip and arranged in the same longitudinal plane and adapted to be passed 105 through the lace and bent longitudinally of the strip toward each other in overlapped relation, to confine the lace between the said tongues and the body of said strip, and said strip being folded to envelop the longitudinal edges of the lace.

In testimony whereof I affix my signature.

MRS. ESTHER B. FINK.
